UNITED STATES PATENT OFFICE.

THOMAS B. ESTEP, OF NORWOOD, OHIO.

VELOCIPED.

SPECIFICATION forming part of Letters Patent No. 499,724, dated June 20, 1893.

Application filed November 21, 1892. Serial No. 452,724. (No model.)

To all whom it may concern:

Be it known that I, THOMAS B. ESTEP, a citizen of the United States, residing at Norwood, in the county of Hamilton and State of Ohio, have invented certain new and useful Improvements in Velocipede-Wagons; and I do hereby declare the following to be a full, clear, and exact description of the invention, reference being had to the annexed drawings, which form part of this specification.

This invention relates to those velocipede-wagons which are capable of being propelled by the joint labor of a number of riders, and my improvement comprises a peculiar combination of cross-handles, reciprocating-shaft, connecting rods, fly-wheels and belts or chains wherewith a very high velocity is imparted to the rear or driving-wheels of the vehicle, as hereinafter more fully described.

In the annexed drawings,—Figure 1 is a side elevation of my improved velocipede, the front of the main frame being broken away and sectioned, so as to expose the pilot wheel and its bearings. Fig. 2 is a plan of the vehicle, portions of the same being removed to show certain details of construction.

The main frame A is provided with any suitable number of seats B, each of which latter may carry one or two riders, who apply their power to cross-handles C, projecting horizontally from a reciprocating-shaft D that occupies the center of the vehicle. This shaft is located a suitable distance above the seats, and is guided in a proper path by standards E, whose lower ends are firmly secured to the main frame.

F F', are other standards secured to said frame and steadied by means of braces f f', short shafts G, G', being journaled in the upper ends of these standards, as seen in Fig. 2. Attached to the inner ends of these shafts are fly-wheels H, H', driven from the shaft D, by connecting rods h, h', and passing around these fly-wheels are belts, bands or chains I, I', that transmit motion to pulleys J, J', fastened upon the rear axle K, to which latter the driving wheels L, L', are rigidly secured.

Projecting from the rear of the main frame is a platform M, having an elevated seat m,

for a person who operates a steering-wheel o at the upper end of a shaft O, the lower end of this shaft being provided with another wheel o' to which is secured at p the mid length of a wire rope P. This rope is carried forward and has its front ends attached at p', p', to a ring R, adapted to turn horizontally in a pair of segmental bearings S, S', secured to the main frame. Ring R has applied to it the axle t of pilot wheel T. U, U', are steps at the rear of the machine.

My velocipede is propelled in the following manner: After the riders have been seated, they grasp the handles C, and work them back and forth in the same manner a boat is rowed, thereby imparting a reciprocating motion to the central shaft D. The connecting rods h h' convert this reciprocating motion of the shaft into circular motion of the fly-wheels H, H', and the latter turn the pulleys J, J', through the instrumentality of the belts or chains I, I'. Now, as these fly-wheels are considerably larger in diameter than the pulleys, it is evident every turn of said wheels produces a number of revolutions of said pulleys, and therefore, a moderate motion of shaft D is sufficient to propel the vehicle at a very rapid speed. The vehicle can be readily diverted from a straight path by the steersman turning the wheel o, which act causes the rope or chain P to revolve the ring R a sufficient distance within its bearings S, S', thereby changing the course of the velocipede, either to the right or left, as may be desired. The vacant space around the standards F, F', may be utilized for carrying baggage, refreshments, &c., thus rendering the vehicle especially serviceable for picnics, &c. In some cases the seats may be dispensed with and the riders stand while operating the handles, which modification of the invention would furnish a hand-car for rail-road purposes, but in this event four wheels would be used, instead of three, as shown. Finally, the pulleys J, J', may be integral with a single sleeve secured to the rear axle K.

I claim as my invention—

The combination, in a velocipede wagon, of a series of standards E, a shaft D recipro-

cating within said standards, and thereby con-
fined to a rectilineal path, lateral handles C
projecting rigidly from said shaft, a pair of
fly-wheels H, H', journaled in bearings on the
5 opposite sides of the shaft, rods h, h', connect-
ing the latter to said fly-wheels, a rear axle K
having the driving-wheels L, L', attached to
it, a pulley J secured to said axle, and end-
less bands or chains I, I', extending from said

pulley to the wheels H, H', all as herein de- 10
scribed, and for the purpose stated.

In testimony whereof I affix my signature in
presence of two witnesses.

THOMAS B. ESTEP.
